UNITED STATES PATENT OFFICE.

HOWARD E. ADT, OF NEW HAVEN, CONNECTICUT, ASSIGNOR TO GEOMETRIC DRILL COMPANY, OF WESTVILLE, CONNECTICUT, A CORPORATION OF DELAWARE.

TAP.

SPECIFICATION forming part of Letters Patent No. 764,409, dated July 5, 1904.

Application filed November 12, 1903. Serial No. 180,922. (No model.)

To all whom it may concern:

Be it known that I, HOWARD E. ADT, a citizen of the United States of America, residing in the city of New Haven, county of New Haven, State of Connecticut, have invented certain new and useful Improvements in Taps, of which the following is a specification.

My invention relates to certain improvements in the construction of screw-cutting taps, the main objects of my invention being to permit and facilitate the grinding and setting up of the cutters to make up for wear, to facilitate their insertion in place, and to improve the means for securing and adjusting the cutters.

While my improvements are applicable to different forms of screw-cutting taps, I have shown them in the accompanying drawings as applied to the construction of taps illustrated in the Patent of W. J. Smith, No. 625,611, dated May 23, 1899.

Figure 1 is a side view of the tap. Fig. 2 is an end view of the cutter end of the tap. Fig. 3 is a longitudinal section on the line 3 3, Figs. 1 and 2. Fig. 4 is an enlarged transverse section on the line 4 4, Fig. 3. Fig. 5 is an inner face view of the locking-plate detached. Fig. 6 is a view of the actuating-collar on the line 6 6, Fig. 3, and a section 30 through the stock and cam-bar, where the cam-bar is connected to the collar by a pin. Fig. 7 is a view of the other face of the collar in a section taken on the line 7 7, Fig. 3. Fig. 8 is a longitudinal sectional view of the cutter end of the tap, and Figs. 9, 10, and 11 are detached views of adjusting and securing collars for the cutters.

The stock A of the tap may be of any suitable construction, and the cutters D may be 40 adjusted radially in their slots in the front end of the stock to the inward or outward positions by various means. In the present instance the cutters are shown as four in number and as bearing at their inner faces against 45 the central longitudinal cam-bar B, by the partial rotation of which the cutters may be projected outwardly against the action of curved

springs S, mounted in the stock, Fig. 8. The free ends of these springs enter holes d in the cutters. To facilitate the introduction of the 50 cutters D into place, Fig. 8, the extreme forward ends of the springs are turned outward, and the mouth of the opening d at the rear end of each cutter is flared toward the back of the cutter, as at d', Fig. 8. The cutters are 55 confined longitudinally between an adjustable ring R on the stock and the plate K, which is secured at the forward outer end of the stock by screws k, Figs. 2 and 3. I make this ring R adjustable longitudinally on the stock, onto 60 which it is set from the forward end of the tap, and I provide means for securing the ring firmly in its adjusted position. When the forward teeth of the tap become too much worn to do their work efficiently, the teeth behind them, which have less work to do, are but 65 little worn. It is customary to put in new cutters when the front teeth of the old cutters are worn away. I take out the cutters when the forward teeth are worn away and I grind 70 down the forward ends of the cutters equally and then put them back in the stock. The ring R is then adjusted forward over the rear ends of the cutter-slots toward the forward end of the tap to grip the cutters between it 75 and the plate K. I then secure the ring R in place, preferably by means of a ring R', Figs. 1 and 3, which is threaded onto a threaded part of the stock behind the ring R. I prefer to form this ring R with inwardly-projecting 80 tongues r, Figs. 8, 9, and 10, to project into the radial slots which receive the cutters D.

Instead of having a ring R' to act as a set-nut for the ring R the latter may be provided with radial securing-screws r', as shown in 85 Fig. 10, these screws, when the ring has been adjusted to its required position, being turned to engage with the stock to so hold the ring. In the modification shown in Fig. 11 the ring R' is shown as threaded internally to engage 90 with the same threaded part of the stock onto which the ring R' is screwed. In this case the tongues r are omitted.

As in the construction illustrated in Patent

No. 625,611 there is secured to the stock, as by radial screws, a face-plate F, and back of this plate is the spring-actuated collar C, by means of which the cam-bar B is rocked 5 through the medium of a radial pin E, Figs. 3, 6, and 7, fitted into a transverse opening in the cam-bar and passing freely through a slot α , Fig. 6, in the stock. The outer end of this pin E fits in a keyway e in the inner face 10 of the operating-ring C. The collar C is provided with a handle C', by which it may be manipulated. In the forward face of this ring C is an annular groove to receive a spiral spring H, one end of which bears against a 15 pin h , Figs. 3 and 7, on the collar C, while the other end bears against a pin f , Fig. 7, which is carried by the back of the face-plate F and projects into the groove in the collar C containing the spring H. This spring tends 20 constantly to turn the collar C in the direction of the arrow, Fig. 7, pressing the pin E against the end of the slot α , Fig. 6, when the operating-collar C is freed from the locking-plate G. This locking-plate G is connected to the 25 stock by a key or feather y , so that while the plate cannot turn upon the stock it can slide longitudinally thereon to a sufficient extent to engage its pin g with or disengage it from a notch c in the rear face of the collar C, Fig. 30. 6. In Fig. 3 the plate G is shown moved back to disengage the pin g from the collar C. The plate G has radial pins 15 projecting through lateral openings a into the hollow interior of the stock, Figs. 3 and 4, and bearing against 35 a shoulder on the piston 16, which is pressed toward the cutter end of the stock by a spring 17. By this means the stop-plate G is constantly pressed up toward the operating-ring C, and when the latter has been turned to 40 such position as will cause the cam-bar B to project the cutters the spring 17 will press the plate G forward to throw the pin g into engagement with the notch c of the collar C, Fig. 6.

45 In order to increase the accuracy of adjustment of the locking-pin g , and so increase the accuracy of the degree of projection of the cutters when the cutter-carrying part and the cam are thereby locked together, I mount the 50 pin g upon a ring G' , which is fitted (and preferably threaded) onto a reduced part 20 of the plate G, as shown in Fig. 3. I also provide at the back of the ring G' an abutment g' , projecting into a slot 18, Figs. 3 and 4, in the 55 plate G. I thread into the plate G screw-stops 19 to bear on opposite sides of the abutment 18, Fig. 4. By adjusting these screw-stops the ring G' , carrying the locking-pin g , can be adjusted rotarilly with great nicety to 60 change the locking-point of the collar C, and consequently the rotary position of the cam-bar B, with relation to the cutters, and there-

fore the degree of projection of the cutters when in cutting position. By adjusting both screws to bear against the opposite faces of 65 the abutment the adjusting-ring G' will be securely locked in its adjusted position. As shown in Fig. 1, I prefer to provide graduations on the plate and ring to show degree of adjustment.

To push the locking-plate G backward to disengage the pin g from the collar C, I prefer to secure to the outside of the plate G longitudinally-slotted bars 21, similar to the bar 6^a of Patent No. 625,611; but the bars 21 70 have secured to their forward ends a ring 22, surrounding the cutter end of the tap and adapted to come into contact with the work or the frame carrying the work, and so push back the locking-plate G against the spring 75 17 to disengage the cutters from the work.

I claim as my invention—

1. A tap provided with a slotted stock and cutters therein, means for setting the cutters in and out radially, an end plate against which 85 the forward ends of the cutters bear, a ring bearing against the back ends of the cutters and adjustable over the cutter-slots toward the forward end of the tap to set the cutters forward when ground at the ends and means 90 for securing the ring in its adjusted position.

2. The combination of a stock and cutters with a rotary cam-piece to actuate the cutters, and a locking-plate for the cam-piece, the locking-plate having a ring threaded into it, 95 and carrying the locking means.

3. The combination of stock and cutters with a rotary cam-piece to actuate the cutters and a locking-plate for the cam-piece, the locking-plate having a ring carrying the locking means and an abutment, with screws in the plate to bear against opposite faces of the abutment to adjust the ring rotarilly and to lock it.

4. The combination of the stock and cutters with a rotary cam to actuate the cutters, a collar to actuate the cam and a longitudinally-movable locking-plate to engage the collar, the locking-plate having a ring carrying locking means, and an abutment and screws in the plate to bear against opposite faces of the abutment to adjust the ring rotarilly and to lock it.

5. The combination of the stock and cutters with a rotary cam to move the cutters to cutting position, and means to lock the cutter-carrying part and the cam together when the cutters are in cutting position, said locking means including a rotarilly-adjustable ring and a plate mounted on the stock, one of these parts having an abutment and the other having adjusting-screws to bear on opposite sides of the said abutment, all substantially as described.

6. A tap provided with a slotted stock and cutters in the slots, an end plate against which the forward ends of the cutters bear, a longitudinally-adjustable ring having tongues
5 projecting into the cutter-slots and bearing against the back ends of the cutters and means for securing the ring in its adjusted position.

In testimony whereof I have signed my name to this specification in the presence of two subscribing witnesses.

HOWARD E. ADT.
